US0D1007437S

(12) **United States Design Patent** (10) **Patent No.:** **US D1,007,437 S**
(45) **Date of Patent:** **** Dec. 12, 2023**

(54) **ELECTRIC CONNECTOR**

(71) Applicant: **Molex, LLC**, Lisle, IL (US)

(72) Inventor: **Daishi Gondo**, Yamato (JP)

(73) Assignee: **Molex, LLC**, Lisle, IL (US)

(**) Term: **15 Years**

(21) Appl. No.: **29/745,812**

(22) Filed: **Aug. 10, 2020**

(30) **Foreign Application Priority Data**

Feb. 13, 2020 (JP) ..... 2020-002682 D

(51) **LOC (14) Cl.** **13-03**

(52) **U.S. Cl.**

USPC **D13/147**

(58) **Field of Classification Search**

USPC D13/147, 154, 120, 133, 148, 149, 182

CPC H01R 11/12; H01R 2107/00; H01R 4/28

See application file for complete search history.

Primary Examiner — Jennifer O King

(74) *Attorney, Agent, or Firm* — Banner & Witcoff, Ltd.

(57) **CLAIM**

The ornamental design for an electric connector, as shown and described.

DESCRIPTION

FIG. 1 is a top perspective view thereof;

FIG. 2 is a bottom perspective view thereof;

FIG. 3 is a front view thereof;

FIG. 4 is a top view thereof;

FIG. 5 is a bottom view thereof;

FIG. 6 is a right-side view thereof;

FIG. 7 is a cross-sectional view taken along line 7-7 of FIG. 3; and,

FIG. 8 is a cross-sectional view taken along line 8-8 of FIG.

6.

A rear view is not provided as it is identical to the front view of FIG. 3. A left-side view is not provided as it is identical to the right-side view of FIG. 6.

1 Claim, 2 Drawing Sheets
